Gottlieb Albert Grupp

By *Samuel L. Siegel*
Attorney.

UNITED STATES PATENT OFFICE.

GOTTLIEB ALBERT GRUPP, OF HEUBACH, GERMANY.

EDGE BINDING FOR COCONUT-FIBER MATS.

Application filed June 21, 1926, Serial No. 117,488, and in Germany September 25, 1925.

The present invention relates to an edge binding for woven and plaited mats such for example as coconut fiber mats of the kind used as door mats, mats for gymnasiums and the like. Mats of this kind are manufactured by weaving or plaiting, and the edge binding at the ends of the mats is formed by stopping back or drawing into the mat the warp threads which project at each end of the mat. This edge binding causes therefore a loss of about 15 to 20 cm. on all the warp threads of each mat as they serve merely to bind the mat and furthermore the drawing in of the binding warp threads is a particularly wearisome and time wasting operation. The greatest disadvantage of this edge binding as hitherto employed is however that it is by no means durable. On the contrary it works loose as a rule even after a short time so that the weft threads lose their hold and the mat quickly becomes useless.

The present invention consists in an edge binding formed from a U-shaped metal clamp, which is affixed to the ends of the mat to be protected by riveting. The clamp is provided on both limbs with inwardly and rearwardly pointing teeth, which enter the mat and securely clamp the strands. It may be conveniently made of steel so as to prevent its bending.

According to this invention the metal clamp may also be provided with a loop or eyelet for hanging the mat up and with revolving handles which have hitherto been wanting on mats of this kind or could only be plaited on to the mat with difficulty.

The advantages of the new edge binding are that in the manufacture of the mats it is no longer necessary to leave long warp threads protruding at the ends of the mat. On the contrary the mats may be woven in the form of an uninterrupted or continuous band and simply be cut off therefrom in the desired lengths. Neither a loss of warp threads nor any interruption in the work of weaving is therefore caused. The application of the metal clamps to the mat is considerably more simple than the production of the edge binding by drawing in the ends of the warp threads as hitherto practised.

The ready punched and bent clamps are drawn over the ends of the mat to be protected and pressed down on the mat in a press, the rivet holes punched through and

the sheet metal rivets riveted over, so that these clamps can be applied to a mat in a very short time.

The subject matter of the invention is illustrated in the accompanying drawing in a constructional form by way of example.

Figure 1 shows in perspective a mat with edges bound by metal clamps according to the present invention,

Figure 2 is a plan view of a clamp opened out flat,

Figure 3 shows the clamp in cross section as applied to a pile mat and

Figure 4 is a perspective view of the clamp.

The new edge binding consists of a U-shaped metal clamp *a*, the limbs of which are provided with inwardly bent teeth *b* turned inwards and backwards towards the bottom of the clamp. These clamps are pushed on to the end of the coco-fiber mat *c* and closed by the pressure of a press, whereby the teeth *b* of the clamp penetrate into the mat so that the warp threads *d* and the weft threads *e* are firmly gripped or clamped between the teeth. Rivets *f* prevent the clamp from springing open and connect it firmly to the mat. To enable the clamps to fit properly smooth edges *h* must be woven at both ends of pile mats.

The clamps may also be provided with eyelets *i* for hanging the mat up or with handles *k* pivoted to the mat. This latter provision is particularly necessary for mats for gymnasiums in which case the mat may be strengthened by hoop iron which may be applied to the underside of the mat longitudinally or diagonally and be attached to the two binding clamps and secured between them say by rivets to the mat itself.

As is plainly shown, particularly in Figs. 2 and 4, each of the teeth *b* has a mat-penetrating portion in the form of a slender, needle-like point, and is gradually and increasingly widened toward its base, so that the edges of the teeth are curved to provide cord-receiving spaces between adjacent teeth. This is of importance because of the peculiar properties of coconut fiber and equivalent materials. Such fiber, as spun into cords for making mats, is relatively poor in the properties of yielding, (extensibility, compressibility and tenacity). The fiber is stiff or brittle and easily broken, and the cords are solid and easily cut. Teeth

formed as shown in the accompanying drawing penetrate deeply into the fiber, the threads or cords being received between adjacent teeth without being broken or cut to any objectionable extent.

I claim:

An edge binding for mats made of coconut fiber and the like, which consists of a U-shaped metal clamp affixed to the mat by 10 rivets, the base of said clamp being adapted to be pressed firmly against the edge of

the mat, and said clamp having teeth provided at its mouth, which teeth have mat-penetrating portions in the form of slender, needle-like points, and are gradually and 15 increasingly widened toward their bases, so that the edges of the teeth are curved to provide cord-receiving spaces between adjacent teeth.

In testimony whereof I affix my signature.

GOTTLIEB ALBERT GRUPP.
